UNITED STATES PATENT OFFICE.

VICTOR SCHLEYER, OF ANDERSON, INDIANA, ASSIGNOR, BY MESNE ASSIGNMENTS, TO
DEAN HILL PUMP COMPANY, OF ANDERSON, INDIANA, A CORPORATION OF IN-
DIANA.

CENTRIFUGAL PUMP.

Application filed March 19, 1923. Serial No. 626,068.

It is the object of my invention to improve and simplify the construction of centrifugal pumps; to prevent whirling of the discharge water from a centrifugal pump 5 while at the same time avoiding the cost and difficulties of the usual multi-vane diffuser; to provide a centrifugal pump particularly adapted for use as a boiler-feed pump, though my invention in many of its features 10 is not limited to a pump for this purpose; to keep the water hot as it passes through the pump, so that the heat the water has absorbed from the feed-water heater may not be lost before the water reaches the 15 boilers, and may even be increased in the pump; to keep an intermittently acting pump from freezing in cold weather, during the intermissions of its action, such as occurs in boiler-feed pumps; and to provide 20 a simple structure in which the steam jacket and the volute discharge-chamber are formed in the same body member.

In carrying out my invention, I provide a 25 centrifugal pump, preferably turbine-driven and preferably of the vertical-shaft type, which may be used as the feed-water pump for a boiler, and especially for a locomotive boiler. This pump may be either single-stage or multi-stage, though for locomotive 30 boiler practice I prefer multi-stage pumps. Each stage of the pump is provided with an anti-whirl vane in its discharge passage, to keep the water from whirling as it is thrown out by the rotating impeller. This vane is 35 of a general involute form, and serves to cause the water to flow outward without material whirling. The discharge chambers of the final stage lead into a volute outlet chamber, which is formed in the main body-member of the pump. In this same body-member 40 is a steam-jacket chamber, which serves to keep the water hot, and even to add to the heat of the water, as the water passes through the pump from the feed-water heater 45 to the boiler.

The accompanying drawings illustrate my invention: Fig. 1 is a vertical central section through a centrifugal pump embodying my invention, with the driving turbine 50 above and the steadyng bearing below shown in elevation, the section being taken substantially on the line 1-1 of Fig. 2; and Fig. 2 is a horizontal section on a slightly enlarged scale, substantially on the line 2-2 55 of Fig. 1.

The pump as shown is a vertical-type pump, having a vertical shaft 10, which at its upper end is connected with a driving turbine 11, and at its lower end is supported in a steadyng bearing 12; and below the 60 steadyng bearing, though it is not a part of my present invention, is a screw-pump 13, which circulates lubricant from a reservoir 14 in the steadyng bearing 12, through such screw-pump 13, by a pipe 15 to the upper 65 bearing 16, and thence back by a pipe 17 to the reservoir 14.

The pump is shown as a multi-stage pump, although my invention is not limited to multi-stage pumps. The pump shown has 70 a plurality of impellers 20 fixed on the shaft 10 one above another, and arranged to throw water outward in the usual manner of impellers from a supply opening 21 near the center to an outer discharge chamber 22 surrounding the impeller. The discharge chamber 22 of each stage except the topmost 75 one communicates by a higher inwardly leading chamber 23 with the supply opening of the next higher impeller, so that the several stages are in series in the usual manner. The inwardly leading chamber 23 usually has return vanes 24, of which there may be an annular series in each such chamber, for directing the water spirally inward toward the supply opening 21 of the next higher impeller, as is the usual practice. The vanes 24 may be integral with either of the adjacent plates 32 and 33 (later described) if such plates are separate from each other as 80 the drawing indicates; but such two plates 32 and 33 on the two sides of a series of vanes 24 are not necessarily non-integral with each other. The supply opening 21 of the lowermost impeller communicates with 85 an inlet opening 25, which when the pump is used for a boiler-feed pump is connected by a supply pipe 26 which leads from the feed-water heater to such inlet opening. This pipe 26 usually leads downward to the 90 inlet opening 25 when the pump is a boiler-feed pump, because the water is hot so that it cannot be effectively lifted by suction. The discharge chamber 22 of the topmost stage communicates circumferentially with a 95 volute outlet chamber 27, as is clear from both Figs. 1 and 2, which volute outlet chamber has the usual tangential outlet passage 28; which when the pump is used as a boiler-feed pump communicates with the boiler.

110

In each of the discharge chambers 22, I provide a single involute vane 30, which guides the water that is thrown outward by the associated impeller 20, and effectively prevents such water from whirling in such chamber. This single-vane construction minimizes the friction-loss in the water being pumped, and effectually prevents such whirling. The inner or receiving end of the vane 30 is at the proper angle to receive the water discharge from the associated impeller, which angle will vary somewhat according to the operating speed of the pump; being designed so that it stands at the normal angle of discharge of such water, so that shock-losses will be largely or wholly avoided. In all the stages except the topmost one, this vane 30 may be placed in any desired circumferential location; but in the topmost stage I prefer to have the outer end of this vane 30 come substantially opposite and in line with the lip 31 formed between the volute chamber 24 and the outlet passage 28, preferably with a slight space 25 between the vane 30 and lip 31, as is clear from Fig. 2.

I am aware that multi-blade diffusers have been used in the discharge chambers of centrifugal pumps; but these have involved considerable expense, and have caused some difficulty in operation because of the tendency of the narrow passages between them to "lime up", especially in using water which has been heated or chemically treated 35 or both, as in boiler-feed water. By my single vane, I not only cheapen the structure while still maintaining an efficient guide and still efficiently preventing whirling, but also find that this "liming up" is effectually prevented.

This vane 30 serves the further function of properly spacing apart the upper and lower plates between which each discharge chamber 22 is formed, and of helping to support the upper plate 32 from the lower plate 33. Since the vane 30 provides support for only a comparatively small circumferential extent, I prefer to supplement this supporting action by additional posts 35, located at 45 spaced circumferential points and extending between the plates 32 and 33. Ordinarily, I prefer to provide two such posts, so that with the vane 30 they will provide a three-point support, the vane 30 and two posts 35 being about equally circumferentially spaced. The posts 35 are preferably of stream-line cross-section, with their long dimension set about parallel to the direction of water flow; or, in other words, set 50 with the relation to the radius substantially as is a section of the vane 30. The vane 30 and the posts 35 in any stage may be integral with the axially adjacent part on either side thereof.

65 Around the pump I provide a steam-

jacket chamber 40, which preferably completely surrounds the pump and extends longitudinally thereof as far as possible. This steam-jacket chamber is supplied with steam by a pipe 41, preferably entering at the top; and has a trapped outlet-pipe 42, preferably communicating with the bottom of the steam-jacket chamber. By this steam-jacket, I secure a number of advantages, particularly when the pump is used as a boiler-feed pump for locomotive boilers. In the first place, it keeps hot the feed water which has been heated in the feed-water heater, so that it will not lose heat before it is discharged into the boiler. In the second place, it not only keeps such feed water hot, but actually helps to heat such feed water; which is especially advantageous if for any reason the feed-water heater fails to heat the water. In the third place, it heats the pump, so that its operation is rendered easier; which is quite an advantage in cold weather, when the lubricant gets stiff. In the fourth place, it keeps the pump from freezing during intermissions in the 75 operation thereof, for a boiler-feed pump is not in constant operation, and the intermissions are often sufficiently long, especially when the locomotive is standing, to allow the water to freeze if that is not otherwise prevented. In this way, the bursting of the pump by reason of such freezing is prevented; and the pump is kept in condition 80 for operation.

In the preferred form of my invention, I provide both the steam-jacket chamber 40 and the volute outlet chamber 27 in the same main cylindrical body-casting 45. This not only simplifies the structure, but also serves to improve the heating effect of the steam-jacket on the water in such volute outlet-chamber; and this heating effect is thus increased at the point where the greatest heat is desired, for the water from the volute outlet chamber 27 is normally fed directly to the boiler, and it is thus heated by the hottest steam in the steam-jacket chamber 40, because the steam entering such steam-jacket chamber does so at the top, close to the volute outlet chamber 27.

110 I claim as my invention:—

1. A centrifugal pump, comprising a vertical shaft, a centrifugal impeller mounted thereon, upper and lower plates between which said impeller rotates, said plates being spaced apart to provide between them a discharge chamber into which said impeller discharges, and a single involute vane located in said discharge chamber and projecting into proximity to said impeller.

115 2. A centrifugal pump, comprising a shaft, a centrifugal impeller mounted thereon, plates between which said impeller rotates, said plates being spaced apart to provide between them a discharge chamber into

which said impeller discharges, and a single involute vane located in said discharge chamber and projecting into proximity to said impeller.

5 3. A centrifugal pump, comprising a shaft, a centrifugal impeller mounted thereon, plates between which said impeller rotates, said plates being spaced apart to provide between them a discharge chamber into 10 which said impeller discharges, a single involute vane located in said discharge chamber, and one or more posts co-operating with said single vane to space said plates apart and support the upper plate from the lower 15 plate.

4. A centrifugal pump, comprising a shaft, a centrifugal impeller mounted thereon, plates between which said impeller rotates, said plates being spaced apart to provide between them a discharge chamber into which said impeller discharges, a single involute vane located in said discharge chamber, and one or more posts co-operating with said single vane to space said plates apart. 20

25 5. A centrifugal pump, comprising a shaft, a centrifugal impeller mounted thereon, plates between which said impeller rotates, said plates being spaced apart to provide between them a discharge chamber into 30 which said impeller discharges, a single involute vane located in said discharge chamber, and one or more posts co-operating with said single vane to space said plates apart, said posts and said vane being circumferentially distributed with respect to one another. 35

40 6. A centrifugal pump, comprising a shaft, a centrifugal impeller mounted thereon, plates between which said impeller rotates, said plates being spaced apart to provide between them a discharge chamber into which said impeller discharges, a single involute vane located in said discharge chamber, and one or more posts co-operating with 45 said single vane to space said plates apart, said posts being of substantially stream-line cross-section, with the major dimension of each post substantially paralleling the flow of water.

7. A centrifugal pump, comprising a

shaft, a centrifugal impeller mounted thereon, plates between which said impeller rotates, said plates being spaced apart to provide between them a discharge chamber surrounding the impeller and into which the 55 impeller discharges, said pump having a volute chamber outward from said discharge chamber and an outlet passage into which said volute chamber discharges, and a single involute vane located in said discharge 60 chamber.

8. A centrifugal pump, comprising a shaft, a centrifugal impeller mounted thereon, plates between which said impeller rotates, said plates being spaced apart to provide between them a discharge chamber surrounding the impeller and into which the 65 impeller discharges, said pump having a volute chamber outward from said discharge chamber and an outlet passage into which 70 said volute chamber discharges, and a single involute vane located in said discharge chamber, said involute vane being arranged with its inner end in proximity to the impeller and its outer end near the lip formed 75 between the volute chamber and the outlet passage therefrom.

9. A centrifugal pump, comprising a shaft, a centrifugal impeller mounted thereon, plates between which said impeller rotates, said plates being spaced apart to provide between them a discharge chamber surrounding the impeller and into which the 80 impeller discharges, said pump having a volute chamber outward from said discharge chamber and an outlet passage into which 85 said volute chamber discharges, and a single involute vane located in said discharge chamber, said involute vane being arranged with its inner end in proximity to the impeller and its outer end substantially opposite and in line with the lip formed between the volute chamber and the outlet passage 90 therefrom.

In witness whereof, I have hereunto set 95 my hand at Indianapolis, Indiana, this 13th day of March, A. D. one thousand nine hundred and twenty-three.

VICTOR SCHLEYER.
